UNITED STATES PATENT OFFICE.

EDWARD J. HUNT, OF WEST ORANGE, NEW JERSEY.

AUTOMATIC CONTROL OF OIL DEHYDRATORS.

Application filed November 4, 1921. Serial No. 512,925.

To all whom it may concern:

Be it known that I, EDWARD J. HUNT, a citizen of the United States, residing at Llewellyn Park, West Orange, in the county 5 of Essex and State of New Jersey, have invented certain new and useful Improvements in Automatic Control of Oil Dehydrators, of which the following is a specification.

10 This invention relates to oil dehydrators of the type disclosed in my prior application, Serial No. 502,258 filed September 21, 1921 and my main purpose is to provide means for automatically starting the operation 15 of the dehydrator as soon as a drop of water is condensed.

A further object of my invention is to cause the operation of an audible or a visual signal to give an indication of the presence 20 of moisture.

In the following detailed description I shall refer to the accompanying drawings, in which Figure 1 is a central vertical sectional view of a short-circuiting or resistance-lowering moisture trap; Fig. 2 is a transverse sectional view on the line 2—2 of Fig. 1; Fig. 3 is a side elevation of an oil dehydrating apparatus embodying my invention and showing the manner of connecting 25 it to a transformer; Fig. 4 is a central vertical sectional view of a modified form moisture trap; and Fig. 5 is a diagrammatic view showing the manner of connecting the latter to a transformer casing; and Figs. 7 30 and 6 are a side elevation and central vertical sectional view respectively of a further modification of the electrodes.

The short-circuiting moisture trap shown in Fig. 1, is placed at the lowest point in the 40 oil circulating system. It comprises a cup-shaped casing 3, having inlet and outlet pipe connections 4 and 5. A solid metal cylinder 6, carried by a stud-bolt 7 constitutes one electrode and a hollow concentric metal cylinder 8, carried by stud-bolts 9, 10 forms the other electrode, the two being separated by a thin sheath 12 of filter paper which extends below the electrodes to the bottom of the chamber of the casing.

45 It is essential that all of the parts of this apparatus shall be absolutely free from moisture. Before the parts are assembled, the cylinder 6 is thoroughly dried and is then wrapped in the sheath 12 of filter paper, the ends of the latter being inserted in the recess 15 and held by the key rod 16.

After the wrapped electrode is thoroughly dried in an oven, it is inserted in the cylindrical electrode 8, which fits tightly thereover, the lower portion being provided with 50 several slots, as indicated at 11, to permit the sides to spring inwardly to form a closer fit. The electrodes are then secured to the wooden cover 18 by means of nuts on the bolts 7, 9 and 10. After being again dried 55 in an oven, the electrodes are inserted in the trap casing and secured by screws 19, a cork gasket 20 ensuring a tight joint.

The moisture trap is inserted in the outlet pipe 21 between the transformer casing 70 23 and the pump 24 connected to the oil dehydrator 25, in the manner illustrated in Fig. 3. The dehydrator and motor-actuated 75 circulating pump are fully described in my prior application Serial No. 502,258 filed Sept. 21, 1921. The electrode terminals 7 and 9 are connected in a circuit 26 with a relay 27. As long as the oil in the transformer casing is free from moisture, the filter paper 12 will remain dry and will 80 serve as a complete insulator between the electrodes and no current will flow in the circuit 26; but in case any moisture condenses in the transformer and descends into the trap 8 it will be immediately absorbed 85 by the filter paper separator 12, which paper has the peculiar property of giving up the dry oil in the presence of moisture and will then become thoroughly water-soaked, thus lowering the resistance between the electrodes 90 6 and 8 and thereby permitting a flow of current in the circuit 26. This energizes the relay 27 and causes the armature 28 to close the circuit 29, thereby lighting the signal 95 lamp 30 and starting the motor pump 31. The dehydrator is kept in operation until the moisture has been completely removed from the oil in the transformer 23.

In the modification illustrated in Fig. 4, the moisture-absorbing sheet of filter paper 12' is in the form of a disk, which is clamped 100 between an electrode in the form of a bolt 7^a having an enlarged disk-like head 7^b and another electrode in the form of a hollow cylinder 8^a having a clamping disk threaded 105 or otherwise secured to its lower end. The filter paper is centrally perforated to pass over the bolt and is tightly clamped between the two disks 7^b, 8^b. The bolt 7^a is insulated 110 from the cylinder 8^a by a suitable cylindrical filler member 35, which may be of wood, the cylinder being surrounded at its upper end

by a wood, cork or other insulating gasket 36, the whole being securely clamped in the cover of the moisture-trap 3^a by means of a hollow nut 37. The electrodes are connected 5 to the circuit wires 26' by means of washers which are connected to the respective electrode.

In Fig. 5 I have indicated diagrammatically the manner in which the moisture-trap 10 shown in Fig. 4 may be connected to a transformer which is located at the top of a pole. The trap is connected to a valved outlet or drain-cock at the bottom of the transformer casing. The dehydrator 25 and its attached 15 motor-actuated pump, which constitute a portable unit are carried upon a truck and its inlet and outlet valved connections 32 and 33, are connected by flexible conduits respectively with the outlet cock 40 of the trap 20 and the filler valve 41 of the transformer casing. I prefer to connect the electrodes to a supervisory circuit 26' in the manner indicated in Fig. 5. This may be a single phase 25 current as supplied from the low tension of the pole-type transformer at 220 volts and 60 cycles. When the oil is in good condition, no action whatever will take place but when a slight amount of moisture enters the oil from condensation or otherwise, it will 30 descend to the bottom of the casing, pass through the drain outlet 21' into the moisture trap 3^a where it will be absorbed by the filter paper separator disk 12', resulting in the immediate lowering of the resistance or 35 the short-circuiting of these electrodes. The circuit 26' will therefore be closed through the short-circuited electrodes, thereby energizing the relay 27' which attracts its armature 28', thus closing a shunt around the 40 electrodes through the signal lamp 30'. Inasmuch as the relay operates practically instantaneously as soon as the moisture is absorbed by the filter paper between the electrodes the gap between the electrodes 45 is instantly short-circuited and consequently no appreciable current will pass through the paper. No chemical action therefore, can take place and no acids can be formed which would be deleterious. Furthermore, the relay will be held in closed 50 position by the short circuit through its armature and the lamp will be lighted until a fresh sheet of filter paper is substituted between the electrodes and until the oil in 55 the transformer tank or casing has been filtered by the dehydrator and brought back to normal dry condition. In supplying the new filter disk, the valve in the drain outlet 21' is, of course, first closed.

60 In Figs. 6 and 7 I have shown another form of electrodes and holder which may be

substituted for those shown in Figs. 1 and 4. In this construction the electrodes 6^c, 8^c are in the form of plates which are bent to provide supporting shoulders 45 which receive the pressure of the inturned lower ends of spring contacts 7^a and 9^a depending from the stud-bolts 7^c and 9^c. The springs thus hold the plates in position and serve as conductors from the electrodes to the stud-bolts. 65 The plates are normally insulated by the filter paper 12'. Instead of filter paper I may employ thin sheets of mica provided with a number of perforations. Normally, the mica separator insulates the plates from each other but when moisture is present the water particles enter the perforations and form a conducting medium between the plates, thus closing the circuit as previously described. In some cases I may even dispense with physical separators and depend upon a narrow gap maintained between the electrodes. 70 75 80

I claim:

1. In a motor-actuated dehydrating device adapted to be connected to an oil container, an electric supply circuit therefor, an electro-magnetic control device in said circuit, a moisture trap having a chamber to entrap any water particles that may be present in the oil, a pair of electrodes connected in circuit with said electro-magnetic device, and a moisture-absorbing medium normally insulating said electrodes, whereby when the presence of moisture impairs the insulating 95 property of said medium an electric current is caused to flow through said electro-magnetic control device. 85

2. In an apparatus for filtering and dehydrating oil, an oil filtering device, a motor-actuated pump therefore, a container connected to said filtering device having a chamber to entrap water particles contained in the oil, electrodes within said chamber separated and normally insulated by a moisture-absorbing medium, and an electric circuit connected to said electrodes including means for starting said motor-actuated pump into operation when said electrodes are short-circuited by moisture absorbed by said medium. 100 105 110

3. In an apparatus for filtering and dehydrating oil, an oil filtering device, a motor-actuated pump therefore, an electric circuit controlling the operation of said motor-actuated pump, electrodes connected in said circuit and normally insulated by a moisture-absorbing medium, and means for subjecting said medium to any moisture that is present in the oil. 115

In testimony whereof I affix my signature.

EDWARD J. HUNT.
